US00D600407S

(12) United States Design Patent
Padain et al.

(10) Patent No.: US D600,407 S
(45) Date of Patent:  Sep. 15, 2009

(54) DEPILATORY DEVICE

(75) Inventors: Chris Padain, Montvale, NJ (US);
Julian Sellers, Birmingham (GB)

(73) Assignee: Reckitt Benckiser (UK) Limited,
Slough, Berkshire (GB)

() Term: 14 Years

(21) Appl. No.: 29/308,632

(22) Filed: Jun. 26, 2008

(30) Foreign Application Priority Data

Jan. 22, 2008 (EP) 000862693-0001

(51) LOC (9) Cl. 28-03

(52) U.S. Cl. D28/44.1; D28/57

(58) Field of Classification Search D28/44-44.1,
D28/45, 56-62; D24/147; 132/73-76.5;
606/131

See application file for complete search history.
